TELEVISION SYSTEM

Karl R. Wendt, Audubon, N. J., assignor to Radio Corporation of America, a corporation of Delaware

Application June 28, 1941, Serial No. 400,178

9 Claims. (Cl. 250—36)

My invention relates to television receivers or the like and particularly to a method of and means for synchronizing cathode ray deflection circuits. The present application describes a simplified form of my invention described and claimed in my copending application Serial No. 400,177, filed June 28, 1941, Patent No. 2,339,536 granted Jan. 18, 1944, and entitled Television systems.

It has been the usual practice to synchronize the cathode ray deflection or scanning at the receiver with the scanning at the transmitter by transmitting to the receiver a mixture of picture signal and synchronizing pulses and by applying the received synchronizing pulses to a blocking oscillator or the like in the deflection circuit for pulling the oscillator into step with the said pulses. This way of synchronizing a deflecting circuit is satisfactory but it usually requires the use of a "speed" or frequency control for the oscillator so that its free running oscillation frequency may be adjusted manually to a frequency close to the rate at which the synchronizing pulses occur.

Also, a circuit so synchronized will fall out of synchronization immediately upon the absence of synchronizing pulses.

An object of the present invention is to provide an improved method of and means for synchronizing a cathode ray deflecting circuit.

A further object of the invention is to provide a cathode ray deflecting circuit which will minimize the tendency to fall out of synchronization immediately upon the failure of synchronizing pulses.

A still further object of the invention is to provide a simplified cathode ray deflecting circuit in which the return line period is made to start at or before the front edge of a synchronizing pulse.

In practicing the invention, I utilize a simplified circuit for producing an oscillator frequency control voltage which changes in value with any change in the phase relation of the incoming synchronizing pulses with respect to the oscillator output. In a specific example, a diode is so connected in the grid circuit of a blocking oscillator that the amount that the grid condenser of the blocking oscillator discharges during a cycle of operation depends upon the phase relation of the applied synchronizing pulses and the oscillator pulses. Thus, the oscillation rate of the oscillator is held in a fixed phase relation to the synchronizing pulses.

The invention will be better understood from the following description taken in connection with the accompanying drawings in which

Fig. 1 is a block diagram of a television receiver embodying my invention,

Fig. 2 is a circuit diagram of the horizontal deflection circuit of Fig. 1 designed in accordance with my invention,

Figs. 3a, 3b, 3c and 3d are curves which are referred to in explaining the invention, and

Fig. 4 is a circuit diagram of another embodiment of the invention.

Referring to Fig. 1, there is shown a television receiver of the usual superheterodyne type comprising a first detector and tuning oscillator indicated at 10, an I.-F. amplifier 11, a second detector 12, a video amplifier 13 and a cathode ray receiver tube 14.

The vertical deflecting circuit 16 and the horizontal deflecting circuit (indicated by the bracket and legend) are synchronized by the usual vertical and horizontal synchronizing pulses which have been separated from the picture signal and from each other by suitable separating and filtering circuits indicated at 18 as is well known in the art.

The horizontal deflecting circuit to which my invention is applied comprises an oscillator 19, a sawtooth generating circuit 21, and an automatic frequency control circuit 22. As indicated schematically by a feedback connection 23, the oscillator pulses are applied to the control circuit 22 whereby its output is impressed upon the oscillator 19 with a value depending upon the phase relation of horizontal synchronizing pulses and oscillator pulses. Thus, the oscillator 19 is held in a fixed phase relation to the synchronizing pulses and the horizontal deflection of the cathode ray of tube 14, likewise, is made to occur in the necessary fixed phase relation with respect to the horizontal deflection at the transmitter.

One embodiment of the invention is shown in detail in Fig. 2 where parts corresponding to those in Fig. 1 are indicated by like reference characters.

Referring to Fig. 2, a separating circuit of the grid-leak biased type is shown at 26. The horizontal synchronizing pulses pass through a small capacity coupling condenser 27 and are amplified by a vacuum tube 28. The resulting positive horizontal synchronizing pulses are applied through a blocking condenser 29 to the plate of a diode 31 having its cathode connected to the grid of the blocking oscillator 19.

Referring now to the oscillator 19, it is of the well known blocking oscillator design comprising an amplifier tube 32 having a feed-back iron core

transformer 33, a grid condenser 34 and a variable grid leak resistor 36.

The blocking rate or frequency of oscillation of a blocking oscillator depends upon the rate at which the blocking charge leaks off the grid condenser 34. In the usual circuit this rate, for a given grid condenser, is determined by the value of the grid leak resistor 36. In the present circuit, it is determined also by the amount the grid condenser 34 can discharge through the diode 31, this amount depending upon the phase relation of synchronizing pulses and oscillator pulses.

It will be seen that in the absence of an oscillator pulse on the cathode of the diode 31, the diode plate is held negative with respect to its cathode by the connection through a resistor 41 to a voltage divider 42. However, upon the occurrence of the negative pulse 43 (Fig. 3b) on the grid of the blocking oscillator, the cathode of diode 31 is driven negative sufficiently to make the diode conducting and the grid condenser 34 discharges through the diode a certain amount. As indicated in volts on the drawings (Figs. 3a and 3b), the amplitude of the blocking oscillator pulse is large compared with that of the synchronizing pulse.

The amount that condenser 34 discharges through diode 31 depends upon the instantaneous value of the synchronizing pulse voltage that is being applied to the diode plate at the instant the negative oscillator pulse 43 (Fig. 3b) occurs. The circuit adjustment is such that the oscillator pulse 43 (Fig. 3b) and the synchronizing pulse 44 (Fig. 3a) occur in substantially the time relation shown in these two figures, that is, the negative portion of the pulse 43 falls on the sloping front of the pulse 44.

From the foregoing it will be apparent that the amount of grid condenser discharge during each oscillator cycle, and therefore the oscillator frequency, will be determined by the phase relation of the synchronizing and oscillator pulses. If the oscillator tends to speed up, there will be less voltage across the diode electrodes and the grid condenser 34 will discharge less, thus holding back the oscillator tendency to speed up. If the oscillator tends to slow down, the opposite action will take place.

The oscillator pulses may be applied to the grid of a discharge tube 46 in the saw-tooth circuit 21. A saw-tooth voltage is produced in the usual way, a condenser 47 being gradually charged through a plate resistor 48 and discharged rapidly, through the tube 46. The resulting saw-tooth wave is shown in Fig. 3c.

The saw-tooth wave from condenser 47 is applied to an output tube 49, which may be operated class A, if desired, or it may be driven to cut-off in accordance with well known practice. The resulting saw-tooth current through the deflecting coils 50 is indicated in Fig. 3d. The return line, indicated at x, is comparatively long and can be shortened only at added expense, as by the use of larger tubes. A comparison of Figs. 3a and 3d shows, however, that the return line starts substantially before the beginning of the synchronizing pulse 44 whereby the return line period is terminated before picture signal for the next scanning line is received. In a conventional circuit, the return line x would start at a later time with respect to the synchronizing pulse 44 as indicated in Fig. 3a by the arrow y and picture signal might occur before the return line ends.

A similar circuit is shown in Fig. 4 where parts

corresponding to those in Fig. 2 are indicated by the same reference characters. In this embodiment of the invention, the plate of the diode 31 is held negative with respect to its cathode between recurring pulses of diode current by means of a resistor 51 shunted by a condenser 52, the condenser 52 being charged by diode current pulses and being discharged slowly through resistor 51. The circuit operation is essentially the same as described for Fig. 2.

It may be noted that, while the D.-C. voltage on the grid of the blocking oscillator tube 32 is the plus B voltage, the actual voltage on this grid is held sufficiently negative by the charge on condenser 34 to block the tube 32 between oscillator pulses.

I claim as my invention:

1. In combination, a blocking oscillator comprising a vacuum tube having a control grid and a plate and a cathode, and having transformer coupled plate and grid circuits, said grid circuit comprising a grid capacitor and a transformer coil in series, a unilateral conducting device connected between said grid and said cathode in the direction to permit electron current flow therethrough from said grid to said cathode and in parallel relation to said grid circuit with respect to said current flow for removing a charge from said capacitor, means for applying control pulses to said device with the correct polarity to make it conducting, and means for maintaining said device in a non-conducting condition between the occurrence of successive control pulses.

2. In combination, a blocking oscillator comprising a vacuum tube having a control grid and a plate and a cathode, and having coupled plate and grid circuits, said grid circuit including a grid condenser and a grid leak resistor, a unilateral conducting device connected between said grid and said cathode in the direction to permit discharge of said grid condenser therethrough, means for applying control pulses to said device, and means for maintaining said device in a non-conducting condition between the occurrence of successive control pulses.

3. In combination, a blocking oscillator comprising a vacuum tube having a control grid and a plate and a cathode, and having coupled plate and grid circuits, said grid circuit including a grid condenser and a grid leak resistor, a unilateral conducting device connected between said grid and said cathode in the direction to permit discharge of said grid condenser therethrough, means for applying to said device control pulses each having a sloping front edge, and means for maintaining said device in a non-conducting condition between the occurrence of successive control pulses whereby it becomes conducting during the occurrence of said front edge but only during the occurrence of a blocking oscillator pulse of comparatively short duration.

4. In combination, an oscillator of the blocking type which includes a condenser that periodically acquires a charge sufficient to block the oscillator for a certain period, a discharge circuit for said condenser, a unilateral conducting device connected in said discharge circuit in series with biasing means to make it conductive only upon the occurrence of a blocking oscillator pulse, and means for impressing control pulses upon said device with the polarity to make it conducting for discharging said condenser by an amount which depends upon the phase relation of said blocking oscillator pulses and said control pulses.

5. In a cathode ray deflection circuit, an oscillator of the blocking type which includes a condenser that periodically acquires a charge sufficient to block the oscillator for a certain period, a discharge circuit for said condenser, a unilateral conducting device connected in said discharge circuit in series with biasing means to make it conductive only upon the occurrence of a blocking oscillator pulse, and means for impressing synchronizing pulses upon said device with the polarity to make it conducting for discharging said condenser by an amount which depends upon the phase relation of said blocking oscillator pulses and said synchronizing pulses.

6. In a cathode ray deflection circuit, an oscillator of the blocking type which includes a condenser that periodically acquires a charge sufficient to block the oscillator for a certain period, a discharge circuit for said condenser, a diode connected in said discharge circuit in series with biasing means to make it conductive only upon the occurrence of a blocking oscillator pulse, and means for impressing synchronizing pulses upon said diode with the polarity to make it conducting for discharging said condenser by an amount which depends upon the phase relation of said blocking oscillator pulses and said synchronizing pulses.

7. In a cathode ray deflection circuit, an oscillator of the blocking type which includes a condenser that periodically acquires a charge sufficient to block the oscillator for a certain period, a discharge circuit for said condenser, a unilateral conducting device connected in said discharge circuit in series with biasing means so that it is conductive only upon the occurrence of a blocking oscillator pulse, and means for impressing synchronizing pulses having a sloping edge upon said device with a polarity that makes it conducting to discharge said condenser by an amount which depends upon the phase relation

of said blocking oscillator pulses and said synchronizing pulses.

8. In combination, a blocking oscillator comprising a vacuum tube having a control grid, a plate and a cathode, and having coupled plate and grid circuits, said grid circuit including a grid condenser, a grid leak resistor through which said condenser may discharge, a second discharge circuit for said grid condenser which comprises a circuit including a diode having a cathode connected to said control grid and having an anode connected to said first cathode, said diode circuit being in parallel relation to said grid circuit which includes said grid condenser, means included in the diode connections for maintaining it in nonconducting condition in the absence of pulses applied thereto, and means for so applying control pulses to said diode that the amount of discharge of said grid condenser depends upon the phase relation of said blocking oscillator pulses and said control pulses.

9. In a cathode ray deflection circuit, a blocking oscillator comprising a vacuum tube having a control grid, a plate and a cathode, and having coupled plate and grid circuits, said grid circuit including a grid condenser, a grid leak resistor through which said condenser may discharge, a second discharge circuit for said grid condenser which comprises a diode having a cathode connected to said control grid and having an anode connected to said first cathode, means included in the diode connections for maintaining it in nonconducting condition in the absence of pulses applied thereto, and means for applying positive synchronizing pulses having sloping sides to the anode of said diode whereby the amount of discharge of said grid condenser depends upon the phase relation of said blocking oscillator pulses and said synchronizing pulses.

KARL R. WENDT.
